UNITED STATES PATENT OFFICE.

WILLIAM MILTON BROWN, CARROLL BURTON, AND SAMUEL C. WEEKS, OF JOHNS-TOWN, PENNSYLVANIA.

SWITCH STAND.

Application filed April 25, 1922. Serial No. 556,409.

To all whom it may concern:

Be it known that we, WILLIAM MILTON BROWN, CARROLL BURTON, and SAMUEL C. WEEKS, citizens of the United States, and residents of Johnstown, in the county of Cambria and State of Pennsylvania, have invented certain new and useful Improvements in Switch Stands, of which the following is a specification.

10 This invention relates to switch stands and more particularly to vertical switch stands having means for preventing the breakage of parts when the switch is trialed.

Switch stands of the class to which this invention belongs are provided with spring pressed members adapted to normally prevent manual operation of the target shaft while being sufficiently resilient to allow the shaft to turn when the switch is trialed.

20 These members are known as spring harps and engage a cam member carried on the lower end of the target shaft.

One object of the present invention is to provide a novel form of spring harp and guide for these switch stands.

Another object is to provide a switch stand having the novel design, construction, and combination of parts hereinafter described and illustrated in the accompanying drawings.

In the drawings, Figure 1 is a side elevation of a switch stand embodying this invention.

Figure 2 is a vertical sectional elevation 35 thereof.

Figure 3 is a sectional plan on the line III-III of Figure 2.

Figures 4, 5, 6 and 7 are detail views of the harp guide.

40 Referring more particularly to the drawings, the numeral 2 designates the hollow base of the stand as a whole, which is composed of a single casting and has a centrally disposed integral tubular standard 3 projecting upwardly therefrom. The bottom wall 4 of the base 2 is provided with a boss forming a bearing for a hollow spindle member 5 which is mounted for rotation within the base and extends upwardly within the

45 standard 3 and is provided with a flange 6 adjacent its upper end adapted to bear against the upper end of the stand. The lower end of the spindle 5 is substantially square in cross section and forms a cam block 7 for a purpose to be described. The

upper end of the spindle 5 is provided with a squared socket 8 adapted to receive the squared lower end of a short sleeve member 9 having a squared aperture extending centrally therethrough for the reception of a square sleeve member 10.

A target shaft 11 extends through the sleeve 10, spindle 5 and base 2, and is adapted to carry the usual target 11^a on its upper end and is provided with an offset head 65 12 having a screw threaded aperture 13 therein for the reception of an adjustable connecting arm 14 adapted to have its forked end pivotally connected to the switch operating rod 15.

The portion of the shaft 11 within the sleeve 10 is of squared cross section so as to form a close fit with the sleeve and carry it with the shaft when the shaft is rotated, while the portion of the shaft below the 75 sleeve 10 and within the spindle 5 is cylindrical so as to rotate relative to the spindle.

From the above it will be readily seen that when the sleeve member 9 is in its lower position, that is fitted within the socket 8 in 80 the upper end of the spindle 5, the spindle must be rotated with the shaft 11. However, it is desired to normally rotate the shaft 11 without rotating the spindle 5 and therefore it is necessary to raise or lift the 85 sleeve 9 out of the socket 8 and for this purpose a lever 16 is pivotally mounted on the sleeve 10 and is connected by links 17 to bosses 18 on the sleeve 9. By lifting the lever 16 upwardly the sleeve 9 will be moved 90 vertically upward along the sleeve 10 until it is free of the socket 8 when the shaft 11 may be rotated to throw the switch. A latch 19 is provided on the sleeve 9 and is adapted to project through a suitable aperture 20 in 95 the lever 16 when the sleeve 9 is in its lower position. An aperture 21 is provided in the latch 19 adapted to receive a padlock 22 or other similar locking device.

In order to prevent manual operation of 100 the switch stand when the lever 16 is locked in its lower position and the sleeve 9 is engaged in the socket 8 in spindle 5, and yet allow operation of the switch stand when it is trialed, a novel spring pressed locking 105 means is provided. This locking means comprises a coil spring 23 mounted in each end of the base 2 and having spring harps 24 mounted in their free ends. The spring harps comprise a head portion 25 and a 110

shank portion 26. The head portion 25 of the spring harps is cut away forming a bearing recess 27 in which is journaled a bearing roller 28 adapted to engage the cam block 7 on the spindle 5. The cam block 7 has its side faces cut away forming roller receiving recesses 29, thereby forming seats for the rollers and causing them to more firmly hold the spindle against rotation.

10 The heads of the spring harps are provided with jaws 30 on their side faces, which are spaced apart to receive the tongue 31 of a harp guide 32. The harp guides 32 comprise a tubular body portion mounted 15 on a vertical pivot 33 and having the tongue 31 projecting outwardly therefrom and upper and lower horizontal flanges 34 and 35, respectively, formed integral with said body portion and said tongue, forming a 20 shroud for and strengthening said tongue and also fitting over top and bottom faces of the jaws 30 to prevent vertical movement of the spring harps. The upper flange 34 is provided with a projection 36 adapted to 25 abut the side wall of the base and limit the rearward movement of the spring harp.

The curved bearing faces of the flanges 34 and 35 of the harp guides are eccentric or cam shaped. That is, they have a greater 30 radius from the center of the pivot 33 to their rear corner than to their forward corner. This novel design of guide flanges serves to hold the spring harps in a central position until the spring 23 is compressed 35 when the forward portion of the guides will be opposite the harps, and since this portion of the guide has a shorter radius it will permit a limited sidewise movement of the harp, thus enabling the point of the cam 40 7 to snap over the wheel 28. After the cam has snapped over the wheel 28 the spring harp will again be moved to its forward position by the action of the spring 7 and the guides will be moved forward so that 45 the rear portions of the flanges 34 and 35 will bear against the harp and prevent sidewise movement thereof.

The tension of the springs 23 against the spring harps is such that the shaft 11 cannot 50 be turned manually unless the sleeve 9 is raised so as to permit rotation of the shaft 11 without operating the spindle 5.

The switch stand shown is what is known as the medium design, and while this design 55 is shown for convenience, it will be understood that the same construction and novel combination of parts may be adapted to what are known as high and low designs by simply making the standard 3, spindle 5, sleeves 9 and 10, and shaft 11 higher or lower as desired, the base remaining substantially as shown in the present construction.

It will be understood that we do not wish 65 to be limited to the exact constructions and

combination of parts shown and described, since various modifications may be made without departing from the scope of the invention as defined in the appended claims.

We claim:—

1. In a switch having a hollow base member, a centrally disposed spindle mounted within said base member, and a cam block on the lower end of said spindle, means for normally holding said spindle against rotation, said means comprising a coil spring mounted in each end of said base, a spring harp extending within and bearing against the outer end of each of said springs, bearing rollers journaled in the outer end of each of said spring harps and adapted to engage the side faces of said cam block, a pair of jaws projecting outwardly from each side of said spring harps, and harp guides pivotally mounted within said base 85 adapted to guide said spring harps, said guides comprising a tubular body portion mounted on a vertical pivot member, and a horizontal tongue portion projecting outwardly at right angles to said body portion 90 and engaged between the jaws on said spring harp.

2. In a switch having a hollow base member, a centrally disposed spindle mounted within said base member, and a cam block 95 on the lower end of said spindle, means for normally holding said spindle against rotation, said means comprising a coil spring mounted in each end of said base, a spring harp extending within and bearing against the outer end of each of said springs, bearing rollers journaled in the outer end of each of said spring harps and adapted to engage the side faces of said cam block, a pair of jaws projecting outwardly from each side of 10 said spring harps, and harp guides pivotally mounted within said base adapted to guide said spring harps, said guides comprising a tubular body portion mounted on a vertical pivot member, a horizontal tongue portion 11 formed integral with said body and projecting outwardly at right angles thereto and adapted to be engaged between the jaws on said spring harp, and upper and lower horizontal flanges of greater width than said 11 tongue formed integral with said body portion and said tongue forming a shroud for and strengthening said tongue and limiting the vertical movement of said spring harps relative to said guides.

3. In a switch having a hollow base member, a centrally disposed spindle mounted within said base member, and a cam block on the lower end of said spindle, means for normally holding said spindle against rotation, said means comprising a coil spring mounted in each end of said base, a spring harp extending within and bearing against the outer end of each of said springs, bearing rollers journaled in the outer end of each 11

of said spring harps and adapted to engage the side faces of said cam block, a pair of jaws projecting outwardly from each side of said spring harps, and harp guides pivotally mounted within said base adapted to guide said spring harps, said guides comprising a tubular body portion mounted on a vertical pivot member, a horizontal tongue portion formed integral with said body and projecting outwardly at right angles thereto and adapted to be engaged between the jaws on said spring harp, and upper and lower horizontal flanges of greater width than said tongue formed integral with said body portion and said tongue forming a shroud for and strengthening said tongue and limiting the vertical movement of said spring harps relative to said guides, and a stop lug on the upper flange of said harp guide adapted to limit the rearward movement of said guide and said harp.

4. In a switch stand having a hollow base member provided with a centrally disposed hollow integral standard projecting upwardly therefrom, a hollow spindle mounted for rotation within said standard and base, a cam block on the lower end of said spindle, a sleeve fitted within a socket in the upper end of said spindle, means for locking said sleeve against rotation relative to said spindle, a square sleeve fitted within a squared aperture in said first named sleeve, and a target shaft passing through said squared sleeve, said spindle and said base, said shaft being squared to fit within said squared sleeve, a coiled spring mounted in each end of said base, a spring harp extending within and bearing against the outer end of each of said springs, bearing rollers journaled in the outer end of each of said harps and adapted to engage the side faces of said cam block, a pair of jaws projecting outwardly from each side of said spring harps, and harp guides pivotally mounted within said base adapted to guide said spring harps, said guides comprising a tubular body portion mounted on a vertical pivot member, and a tongue portion projecting outward from said body portion and engaged between the jaws on said spring harp.

In testimony whereof we have hereunto set our hands.

WILLIAM MILTON BROWN.
CARROLL BURTON.
SAMUEL C. WEEKS.
